UNITED STATES PATENT OFFICE.

GEORGE S. BATCHELLER, OF MILLBURY, MASSACHUSETTS.

DESIGN FOR A CLIP FOR WASHING-MACHINES.

SPECIFICATION forming part of Design No. 26,110, dated September 29, 1896.

Application filed August 11, 1896. Serial No. 602,454. Term of patent 7 years.

To all whom it may concern:

Be it known that I, GEORGE S. BATCHELLER, a citizen of the United States, residing at Millbury, in the county of Worcester and State of Massachusetts, have invented or produced a new and useful Design for a Securing-Clip for Washing-Machines, of which the following is a specification.

Supporting-clips of my design have been especially devised for adjustably securing washing-machines in place in the tubs where they are to be employed.

The accompanying drawing shows a perspective view of a supporting-clip for washing-machines embodying my design.

The leading features of my design for a supporting-clip for a washing-machine comprise a main or body portion 10, a supporting ledge or projection 11, and a downwardly-extending retaining-lip 12. The supporting-

ledge 11 and the retaining-lip 12 are provided with a suitable stiffening-head 13. Extending from the rear face of the body portion 10 are one or more longitudinally-slotted fastening-sections 14, which, in the use of the clip, are adjustably connected to the base-board of a washing-machine.

What I claim, and desire to secure by Letters Patent of the United States, is—

The design for a securing-clip for washing-machines, substantially as shown and described.

In testimony whereof I have hereunto set my hand in the presence of two subscribing witnesses.

GEORGE S. BATCHELLER.
